[57] CLAIM

The ornamental design for an automobile tire, as shown and described.

DESCRIPTION

FIG. 1 is a front and left side perspective view of an automobile tire showing our new design, the tread pattern being repeated throughout the circumference of the tire;

FIG. 2 is an end elevational view thereof;

FIG. 3 is a side elevational view thereof;

FIG. 4 is a side elevational view thereof, from the side opposite that of FIG. 3; and

FIG. 5 is a top plan view thereof in inverted condition.

FIG. 1

FIG. 2

*FIG. 3*FIG. 4

FIG. 5
